UNITED STATES PATENT OFFICE.

OSCAR L. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

SAFETY DEVICE FOR CARDING-MACHINES.

1,112,829.

Specification of Letters Patent.

Patented Oct. 6, 1914.

Application filed October 1, 1908. Serial No. 455,761.

To all whom it may concern:

Be it known that I, OSCAR L. OWEN, a citizen of the United States, residing at Whitinsville, in the county of Worcester 5 and Commonwealth of Massachusetts, have invented certain new and useful Improvements in Safety Devices for Carding-Machines, of which the following is a full, true, and concise specification.

- 10 The invention is a safety device for controlling the cylinder doors of carding machines, and more particularly consists of the organization of means hereinafter described for interlocking the said door with the 15 power-controlling device, whereby the door is locked shut while the power is on and the power is held off so long as the door is open, thereby guarding against injury both to the machine and the operator.
- 20 The invention further includes means, combined with the foregoing, whereby the power may be turned partially on while the door is open, but under restricted conditions, so as to enable the carding cylinder to receive 25 a suitable motion while the stripping or grinding attachment is operating thereon through the open doorway.

These and further features of construction and operation constituting the present 30 invention, will appear from the description which follows, and are pointed out in the accompanying claims.

Referring to the drawings forming a part hereof, Figure 1 illustrates a form of my 35 invention in side elevation, and so much of a carding machine as is directly related thereto; Fig. 2 is a top plan of the same parts; Fig. 3 is an end elevation thereof; Fig. 4 is an enlarged detail in side elevation of the 40 interlocking members; Fig. 5 a similar detail in end elevation, parts being in section; Fig. 6 is a detail in plan of same parts, in their door-blocking position; and Fig. 7 is a sectional detail through the blocking sleeve.

45 The main casing of the carding machine is designated 1 and its cylinder-door 2 is located, as usual, in the front wall thereof adjacent to the casing 1^a of the doffing cylinder.

50 In the operation of carding machines, the cylinder-door is opened from time to time for the purpose of stripping or grinding the teeth of the carding cylinder which revolves within the main casing 1, and if it is not closed before the machine is again set

to work, the stripings falling from the flats, shown at 3, will accumulate on top of it, where they will be likely to fall through the opening and injure the carding cylinder, or, if they do not fall into the opening, they are 60 then likely to conceal it, so that the operator may inadvertently thrust his hand into the revolving cylinder, when he attempts to remove them. My invention aims to remove the danger from this cause by connecting or 65 correlating the said door or any similar protecting covering of moving parts with the device which controls the driving power of the machine, first, so as to prevent the operation or complete operation, of said device 70 while the door is open, and, second, after it has been operated, to prevent the opening of the door, so that at no time will it be possible for the machine to be left running with the protecting-door open. To this end, the 75 said door is provided with a lateral pin 4, which through the connecting-rod 5, operates a blocking-member 6, at the side of the machine. As herein shown, the blocking member is a lever of the first class, fulcrumed on a depending part of a bracket 7 and having a laterally enlarged head 6^a. The bracket 7 is secured to the card-arch, 80 as shown, and the lever is longitudinally off-set so that its head will be outside the vertical plane of said arch while its lower extremity will be in line with the pin 4 and connecting-rod 5. In the position to which the lever is moved by opening the door, which is shown by Fig. 6 and by the dotted 85 lines of Fig. 4, its head 6^a assumes a position, as an abutment, directly in the path of movement of the power-controlling device or some part or member geared to or moving with it.

90 The power-controlling device may, within the scope of this invention, consist of any suitable means for turning off and on the driving power of the machine, being preferably also of a kind that is adapted for an intermediate setting for the purpose of driving the machine at less than full speed. Specifically, such a device is a belt shipper, co-operating in the usual manner with the fast and loose pulleys (8 and 9) on the shaft of the carding cylinder, and includes a shipper fork and support 10 therefor which is adapted for movement along the horizontal slideway 11 which projects laterally from the bracket 100 above referred to. Movement is imparted 105 to the shipper fork by a lever 12 which is 110

to the shipper through the crank and link connection 12, by means of a rock-shaft 13 which is the controlling shaft of the power device, being also carried by the bracket 7. 5 The parts just described are so arranged that a half turn of the shaft shifts the belt completely from one pulley to the other, while a quarter turn or less will shift the belt to a middle position, wherein the machine will be driven at less than full speed on account 10 of the slippage.

The control shaft 13 extends parallel with the card arch and carries hand-wheels 14 at its ends, one of the hand-wheels being adjacent to the stripping door. At an intermediate point the said shaft carries a lateral projection or arm 15, which is the member, above referred to, of the power-controlling device that is blocked by the head of the lever 6. This abutting member normally revolves a half revolution, as above stated, when the power is turned full on, but when the door is open and the abutment formed by the lever 6 is in its blocking position, the abutting member encounters it as indicated in Fig. 6, so that the turning on of the power is thereby arrested. The blocking action thus established, however, is not intended to be positive, except as to the full belt slipping 20 movement of the shaft, and the parts are arranged so that a preliminary or partial rotation of the control shaft may take place, in the direction of turning on the power, notwithstanding the condition of the door and 25 the position of its operated lever 6. This preliminary or partial movement is permitted in order to enable the power to be turned partially on, so that the carding cylinder may be slowly revolved while the grinding 30 or stripping operation is going on.

The grinding or stripping apparatus is in the nature of an attachment, not herein shown, but adapted to be supported in the brackets 16 (Fig. 1) where it can work on the 35 carding cylinder through the open door, in the usual manner, and it is intended to be driven by a belt running in the grooved pulley 17 on the loose pulley 9. This pulley is driven by partial engagement with the driving belt when the control shaft is in its slow 40 speed position. It is preferred that this initial movement of the control shaft to its slow speed setting shall take place against some resistance, though this is not essential, and 45 for this purpose one of the two engaging parts is made to yield resiliently to the other. In the form herein illustrated, the said arm 50 15 is made the yielding member, and the manner of its support for this purpose is as follows: The said arm is carried by or formed as a part of a rotatable sleeve 18 which is carried by the control shaft between two fixed collars 19 and 20 thereon. The sleeve is provided with a keyway that is 55 60 65 engaged by a complementary lug 21 on the

collar 19, the keyway being of sufficient arcuate length to permit about a quarter rotation of the sleeve on the shaft. A spring 22, connected to the sleeve and the other collar 20, tends to urge the former and its arm 15 70 toward the blocking lever 6, the position shown by Fig. 7, so that the said arm may yield relatively to the shaft after engaging the blocking lever, to allow the rock-shaft to turn for about a quarter turn, as shown in 75 Fig. 5, or until it has shifted the belt partly onto the fast pulley, whereupon the positive engagement of the lug 21 with the end of its keyway prohibits further movement. In this position the control shaft must be held 80 by the operator against the tension of the spring and the latter may, if desired, be made strong enough to restore the belt to the loose pulley when released.

By shutting the door and thereby replacing the lever 6 to its full line position of Fig. 4, the rock-shaft may obviously be rocked its complete half-turn and the power thereby turned full on. For the purpose of then locking the door against opening, the power device is likewise provided with a blocking or abutted member which is moved by the control shaft into a position in the path of one of the door-operated members, such as the lever 6. This blocking or abutted member, shown at 23, is conveniently formed as a part projecting from the sleeve 18 at a right angle to the arm 15, being located so that it can move into the space just behind the lever 6, when the cylinder door is closed. 100 This position is indicated by the dotted lines of Fig 5, the member 23 not being affected by the rotary yielding action of the sleeve, since it is only adapted to resist movement of the said lever in a rearward direction, 105 longitudinally of the shaft.

It will be observed that in the above described embodiment of my invention, the lever 6 and the sleeve 18, with its two projecting arms 15 and 23, constitute mutually 110 interlocking abutting and abutment members, each adapted to control or block the other, in their alternate positions, but it is to be understood that the invention is not limited to this construction or arrangement, 115 and that separate instrumentalities can be provided for the respective blocking actions within the scope of the following claims.

Having described my invention, what I claim and desire to secure by United States 120 Letters Patent, is:

1. In a carding machine, a power-controlling device comprising a manually operated rock-shaft, having an abutment member, held against longitudinal movement on the 125 shaft, but having limited rotary motion thereon, and a spring urging said member to one extreme of its rotary movement, in combination with a card cylinder door, provided with a corresponding abutment mem- 130

ber coöperating with said first mentioned member to block opening of the door in one position and to permit partial rotation of the rock-shaft against the spring when in its other position.

2. In a carding machine, a power-controlling device comprising a manually-operated rock-shaft having an abutment member capable of relative rotary movement thereon, and a spring on said rock-shaft adapted to resist relative rotary movement between the same and said abutment member, in combination with a card cylinder door provided with a corresponding abutment member coöperating with said first mentioned abutment member to obstruct rotational movement thereof against the tension of said spring.

3. In a carding machine, a power-controlling device comprising a manually-operated rock-shaft having an abutment member capable of rotational movement thereon, and a spring between said abutment member and rock-shaft to urge the same toward one extreme of its relative rotary movement, in combination with a card cylinder door provided with a corresponding abutment mem-

ber coöperating with said first mentioned abutment member to block opening of the door in one position and to permit partial rotation of the rock-shaft against the spring when in its other position.

4. In a carding machine, a power-controlling device comprising a manually operated rock-shaft, two collars thereon, an abutment member between said collars adapted for relative rotary motion upon the rock-shaft and a spring between said abutment member and one of the collars adapted to urge said member to one extreme of its rotary movement, in combination with a card cylinder door provided with a corresponding abutment member coöperating with said first rotary abutment member to block opening of the door in one position and to permit partial rotation of the rock-shaft against the spring when in its other position.

In testimony whereof, I have signed my name to the specification in the presence of two subscribing witnesses.

OSCAR L. OWEN.
